US00D557062S

(12) United States Design Patent (10) Patent No.: US D557,062 S
(45) Date of Patent: * Dec. 11, 2007

(54) CASSEROLE

(75) Inventor: Jacques Henry, Marcigny (FR)

(73) Assignee: Emile Henry Industrie (FR)

() Term: 14 Years

(21) Appl. No.: 29/234,255

(22) Filed: Jul. 15, 2005

(51) LOC (8) Cl. 07-02

(52) U.S. Cl. D7/360

(58) Field of Classification Search D7/323, D7/393, 354-360, 538-540, 542-545, 547, D7/548, 560, 565, 566, 570, 584, 586, 587, D7/602; 62/457.6; 99/339, 534; 126/369, 126/385.1; 220/23.4, 23.8, 574, 575

See application file for complete search history.
